UNITED STATES PATENT OFFICE.

MOSES M. MARCUSE, OF NEW YORK, N. Y., ASSIGNOR TO WEST DISINFECTING COMPANY, OF NEW YORK, N. Y., A CORPORATION OF NEW YORK.

DISPENSING CABINET.

Application filed January 23, 1922. Serial No. 531,811.

To all whom it may concern:

Be it known, that I, MOSES M. MARCUSE, a citizen of the United States, and a resident of New York city, in the county and State 5 of New York, have invented certain new and useful Improvements in Dispensing Cabinets, of which the following is a specification.

This invention relates to dispensing cabinets of that class used for delivering interleaved sheets and particularly to an attachment or insert which can be readily attached to existing cabinets to facilitate the withdrawal of the sheets by reducing friction.

10 A large number of this general type of cabinets which are now in use are not provided with any friction reducing means, the interleaved sheets being withdrawn through a dispensing opening usually formed in the 15 bottom of the container. When, therefore, the cabinet has a considerable supply of towels therein, the pressure exerted by the combined weight of the towels makes the withdrawal of the towels difficult and oftentimes the towels are thereby torn or mutilated during withdrawal.

It is therefore the primary object of my invention to provide a separate arrangement in the form of an attachment which may be 30 quickly and conveniently applied to the types of dispensing cabinets now universally employed and which will make these cabinets more efficient by reason of the elimination, or at least, a considerable reduction, in 35 the friction occasioned when a sheet is withdrawn.

In carrying out my invention, I provide in general a pair of rollers journalled in suitable supports, which supports carry means 40 for securing them to the dispensing cabinet at the dispensing opening thereof. The sheets when withdrawn are adapted to pass over one or the other of the rollers and the supply of towels to be partially supported by 45 the rollers thereby also facilitating the withdrawal of a single towel.

Various other advantages and features of construction of my invention, as well as the manner of using the same will be more 50 completely described in the accompanying specification and illustrated in the drawings in which:

Fig. 1 is a fragmentary section of a cabinet equipped with my invention,

55 Fig. 2 is a longitudinal section thereof

with my improved attachment shown in elevation,

Fig. 3 is a fragmentary perspective view 60 of this improved attachment removed from the cabinet,

Fig. 4 is a view similar to Fig. 1 of a slightly modified form of my invention,

Fig. 5 is a view similar to Fig. 2 illustrating this modified form,

Fig. 6 is a fragmentary perspective view 65 of this modified form of attachment removed from the cabinet,

Fig. 7 is a view similar to Fig. 1 of still another modified form of construction,

Fig. 8 is a view similar to Fig. 2 of this 70 second modification,

Fig. 9 is a fragmentary separated perspective view of this second modified form of attachment,

Fig. 10 is a view similar to Fig. 1 of another modified form of construction, and

Fig. 11 is a perspective view of this modified form of attachment.

Referring now more particularly to Figs. 1 to 3, the first form of my improved invention will be described. In these figures the reference character 10 indicates a dispensing cabinet in the form of a box-shaped casing, this being representative of the types of cabinets now in use, the bottom thereof 85 being provided with a longitudinal delivery opening 11 through which the individual towels of a stack of interleaved towels 12 are withdrawn.

Referring now particularly to Fig. 3, it 90 will be seen that my improved attachment consists of a pair of plate-like supporting members 13 suitably apertured to receive the shafts 14 of a pair of rollers 15, thereby providing a mounting or support for these rollers enabling them to be freely rotated. As illustrated clearly in Figs. 1 and 3, these rollers are separated a distance corresponding to the width of the delivery opening 11. Each supporting plate 13 has secured thereto by soldering or otherwise, a fastening member 16, here shown in the form of a wire.

In applying my improved attachment the same is placed on the bottom of the cabinet 105 10 with the rollers disposed parallel with the edges of the delivery opening and with the free ends 17 of the attaching members projecting downwardly through the delivery opening. The ends of these wire attaching 110

members are then bent upwardly to clinch the attachment in place. This is clearly illustrated in Figs. 1 and 3.

In Figs. 4 to 6 the end plates 13 of the attachment are shown as each provided with a tongue 18 which is adapted to be inserted downwardly through the delivery opening 11 and bent upwardly around the ends of the cabinet 10 as clearly illustrated in Fig. 6. 10 This is sufficient to hold the attachment firmly in place in its position immediately above the delivery opening. In every other respect this form of my invention is the same as the form illustrated in Fig. 3 and 15 therefore like numerals refer to like parts.

Referring now more particularly to Figs. 7 to 9 inclusive the third form of my invention will be described. In this form there is provided a pair of end plates 19 20 each provided with a tongue 20 similar to the form illustrated in Figs. 4 to 6, which is adapted to be bent around the end of the cabinet. Associated with each end plate 19 is a plate 21 adapted to rock about a pin 22 25 by which it is pivotally connected to the end plate 19. Mounted upon the plate 21 are a pair of rollers 23 which as in the other forms are adapted to freely revolve.

In using the form of my invention just 30 described the roller carrying plates 21 are adapted to be rocked as the towels are withdrawn, the towel being withdrawn passing over one roller while the other roller is rocked to a raised position to lift the stack 35 of towels and relieve somewhat the pressure imposed on the towel being withdrawn.

Referring now to Figs. 10 and 11, the 40 fourth form of my invention will be described. In this form I employ a pair of roller carrying plates 24 having extended ends 25 which are of sufficient length to fit snugly against the side walls of the cabinet 10. Rollers 26 are mounted on these plates so as to rotate freely and in every 45 other respect this form of my invention functions similarly to the forms illustrated in Figs. 1 to 6. By forming the roller carrying plates 24 with extended ends 25, retaining means is provided and the necessity 50 for separate attaching means is eliminated as the apparatus will be held properly in place within the cabinet by reason of its size, the roller carrying plates 24 being spaced longitudinally by the rollers 26 so as 55 to dispose these plates immediately adjacent the end walls of the cabinet 10.

In the first two and last form of my invention it is obvious that the towel being withdrawn passes over one or the other of 60 the set of rollers associated with the delivery opening and because the rollers are freely revoluble the friction is reduced and the withdrawal of the towel facilitated. Furthermore, the pair of rollers associated 65 with each delivery opening support the

stack of towels spaced from the delivery opening, also facilitating the withdrawal of a towel. From the foregoing it will be obvious that I have provided an attachment 70 which may be efficiently used in connection with the dispensing cabinets now already in use and one which furthermore may be conveniently and quickly put in place. The attaching means in the form of clincher wires in the front form and tongues in the second and third forms provide ample means 75 for holding the attachment in place immediately above the delivery opening of the cabinet. Likewise the attaching means in the form of the extended ends of the plates 80 24 in the last form of my invention provides means for conveniently retaining the attachment in place above the delivery opening of the cabinet.

While I have illustrated several embodiments of my invention, I do not wish to be unnecessarily limited to these specific constructions but reserve the right to make such changes in the form thereof as may come within the purview of the accompanying claims.

Having thus described my invention, what I claim is:

1. An arrangement for use in combination with a dispensing cabinet provided 95 with a delivery slot comprising a pair of spaced rollers, means for mounting said rollers and disengageable means for rotatably securing said arrangement to said cabinet adjacent said delivery slot.

2. An arrangement of the class described for use in connection with a dispensing cabinet provided with a delivery slot comprising a pair of spaced supporting plates, rollers disposed between said plates and supported thereby and means carried by said plates and projecting through the delivery slot of said cabinet for securing said arrangement in position immediately above said delivery slot.

3. A device for use in connection with a dispensing cabinet provided with a delivery slot, said device comprising a pair of spaced plates, a pair of spaced parallel rollers, means for mounting said rollers on said plates, said device being adapted to be positioned within said cabinet immediately over said delivery slot and means carried by said plates projecting through said delivery slot and adapted to be bent back 120 against said cabinet for securing said device in place.

4. An arrangement of the class described for use in combination with a dispensing cabinet provided with a delivery opening, 125 said arrangement comprising a pair of spaced supporting plates, a pair of spaced parallel rollers mounted on said supporting plates, lips formed integrally on said plates, said arrangement being adapted to be placed 130

within said cabinet over said delivery opening with said lips projecting through said opening and secured in place by bending said lips upwardly against said cabinet.

5. An arrangement of the class described for use in combination with a dispensing cabinet provided with a delivery slot, said arrangement comprising a pair of plates, a pair of roller supporting plates pivotally secured to said first mentioned plates, a pair of spaced parallel rollers mounted on said roller supporting plates and means carried by said first mentioned plates and

adapted to project through said delivery slot for supporting said arrangement with- 15 in said cabinet immediately over said de-
livery slot.

6. An arrangement for use in combination with a dispensing cabinet provided with a delivery slot comprising a separate unit 20 adapted to be placed within said cabinet, said unit comprising a pair of spaced rollers, means for mounting said rollers and means for retaining said unit in place within said cabinet adjacent said delivery slot. 25

MOSES M. MARCUSE.
